UNITED STATES PATENT OFFICE.

GEORGE L. BENNETT, OF CHICAGO, ILLINOIS.

AIR-PUMP.

SPECIFICATION forming part of Letters Patent No. 775,885, dated November 22, 1904.

Application filed February 8, 1904. Serial No. 192,713. (No model.)

To all whom it may concern:

Be it known that I, GEORGE L. BENNETT, a citizen of the United States, residing at Chicago, county of Cook, and State of Illinois, 5 have invented a new and useful Improvement in Air-Pumps, of which the following is a specification.

My invention is related to gasometers and air-compressors used in the practice of surgery and dentists to administer anesthetics by means of compressed air, also in connection with an atomizer or a blowpipe in mechanical dentistry.

It is often necessary to quickly reinflate the bell during an operation of any character, and when using the old style of gasometers fitted with automatic inlet valves or cocks they have been found to consume too much time in manipulating them, and it is often necessary to 20 change the location of the gasometer from one room or place to another.

The objects of my invention are to provide a combined handle and valve fixed to the top of the floating bell in such manner that when 25 the bell is lifted to inflate it the valve will be opened at the same instant.

I attain these objects by a mechanism illustrated in the accompanying drawings, in which—

30 Figure 1 is a vertical sectional view of a gasometer, showing my improvement fixed to the crown of the bell in section. Fig. 2 is a top view of the valve and handle. Fig. 3 is a top view of the valve-tube, showing one of the guide-bars.

Similar letters refer to similar parts throughout the several views.

In the drawings is shown a gasometer having a floating bell A, a liquid-tank A', an inner chamber A², water-space w, and discharge-pipe B. The arrows indicate the direction the air takes to escape through the central tube B in the inner chamber.

A stud b, having a tenon b' on its upper end, 45 is fixed to the crown of the bell A by a nut l and screw b². The handle a is mortised at h i to fit the tenon b'. The ends of the mortise are cut at an angle to permit the handle to be moved up and down on the pivot-pin k. The 50 outer end of the handle is fitted with a thumb-

screw c. The valve-tube f is fixed in the crown of the bell and is provided with guide-bars g. The valve m is fixed to the stem p by a nut and screw n. The top of the valve-stem is provided with a disk head d. A coil-spring e is placed around the stem between the guide-bar and the head. The stem is adapted to slide in the orifices in the guide-bars.

In operation, the bell being deflated, it is intended to be lifted by the handle simultaneously with the opening of the valve. The operator grasps the handle and lifts on it. This causes the screw e to come in contact with the head of the valve-stem, pushing it downward, opening it, and holding open till the bell is 65 sufficiently inflated. The handle being released will fall back to its normal position. The spring assisted by the air-pressure will close the valve, and the bell will remain up inflated. When it is necessary to deflate the 70 bell, the operation should be reversed.

When it is required to move the gasometer from place to place, the bell may be strapped to the tank or otherwise secured, the thumb-screw being turned out so that it will not come 75 in contact with the valve-head, when it may be lifted by the handle and carried about.

Having described my invention and its operation, what I claim as my invention, and wish to secure by Letters Patent, is—

The combination in an air-pump of the movable handle having a mortise adapted to receive a tenon, the thumb-screw in the outer end of said handle, the stud having a tenon adapted to fit in said mortise, the handle being pivoted to said stud, the stud fixed to the crown of the floating bell, the valve-tube having guide-bars provided with means for receiving a slideable valve-stem, said valve-tube fixed to the crown of bell, the outwardly-closing valve having a stem carrying a disk head adapted to engage the thumb-screw, the valve-stem provided with an actuating-spring, the bell adapted to float in the liquid-tank substantially as described.

GEORGE L. BENNETT.
